UNITED STATES PATENT OFFICE.

JOHN SERAGE RITCHIEY AND CLYDE PRESTON WAGNER, OF JOPLIN, MISSOURI.

PAN-CLEANING MACHINE.

1,183,672.

Specification of Letters Patent. Patented May 16, 1916.

Application filed September 4, 1915. Serial No. 49,108.

To all whom it may concern:

Be it known that we, JOHN SERAGE RITCHIEY and CLYDE PRESTON WAGNER, citizens of the United States, residing at 5 Joplin, in the county of Jasper and State of Missouri, have invented certain new and useful Improvements in Pan-Cleaning Machines, of which the following is a specification, reference being had to the accompanying drawings.

This invention relates to certain improvements in pan cleaning machines and has relation more particularly to a machine of this general character especially designed 15 and adapted for use in connection with the flat pans generally employed in baking operations.

It is also an object of the invention to provide a device of this general character 20 having novel and improved means whereby a pan, after being cleansed, has applied thereto a coating of oil, such as cotton seed so that the pan is ready for use for baking when delivered from the machine.

The invention consists in the details of construction and in the combination and arrangement of the several parts of our improved pan cleaning machine whereby certain important advantages are attained and 25 the device is rendered simpler, less expensive and otherwise more convenient and advantageous for use, all as will be hereinafter more fully set forth.

The novel features of the invention will 30 be carefully defined in the appended claims.

In order that our invention may be the better understood, we will now proceed to describe the same with reference to the accompanying drawings, wherein—

Figure 1 is a longitudinal vertical section taken through the machine as herein disclosed; Fig. 2 is an enlarged fragmentary sectional view of an extremity of the oiler brush and its concomitant parts as herein included. Fig. 3 is a fragmentary sectional view of the extremity of the oiler brush remote from that shown in Fig. 2.

As disclosed in the accompanying drawings, 35 1 denotes a side beam with which coacts the tie members 2 and having coacting therewith the supporting uprights 3 with which the connecting members 4 coact. The supporting uprights in longitudinal alinement are connected by the horizontally disposed beams 5 positioned a predetermined

distance below the beams 1 and in parallelism therewith. Adjacent extremities of the beams 1 rotatably support the shaft 7 provided in close proximity to the inner faces of the beams 1 with the sprockets 8 and around each of said sprockets 8 is disposed the endless chain 9, the upper stretch of which being substantially flush with the upper longitudinal edge of the adjacent beam 1. The chain 9 is also directed around a sprocket 10 in longitudinal alinement with the sprocket 8 and affixed to the shaft 11 adjustably mounted within the longitudinally disposed recess 14 produced in the end 70 of the beam 1 opposite to the shaft 7. Coacting with the shaft 11 is the adjusting member 15 whereby it will be perceived that the requisite tension may be applied to the endless chain 9.

The machine as herein disclosed is particularly adapted for use in connection with the flat pans generally employed in baking operations in the manufacture of crackers or the like and the chain 9 is adapted to 80 have positioned thereon a pan P to be cleansed so as to cause the same to travel longitudinally of the beams 1 and beneath the members to be hereinafter more particularly referred to.

Each of the beams 1 at substantially its longitudinal center is provided with the upstanding transversely alined bearing 17 in which is suitably mounted for vertical adjustment the shaft 18 having affixed thereto 90 the drum 19 from which substantially radiate the wire bristles 20 adapted to engage the upper surface of the pan P to scrape therefrom all waste matter which may be adhering thereto, and it is to be particularly noted that the wire bristles 20 are irregularly bent in all directions so that the entire surface of the pan will be operated upon.

Operatively engaged with the shaft 18 100 through the medium of the chain 26 is a shaft 28 having each of its end portions rotatably supported by a bar 29 carried by a side beam 1. Affixed to the shaft 28 is the drum 30 provided with the cloth windings 105 31 adapted to serve as a buffer and contact with the pan P for wiping the upper surface thereof and thus effectively cleans the pan. The shaft 28 travels in the same direction as the shaft 18 and at the same axial 110 speed.

In order to prevent the upper stretch of

the chain 9 from sagging and thus assure a pan P to be held solid against the pressure of the bristles 20 and buffer 31, we find it of particular advantage to dispose beneath the 5 upper stretch of the chain 9 the elongated metallic strip 32 secured to the brackets 33, said brackets being secured to the inner faces of the beam 1 and are capable of vertical adjustment, as is indicated at 34, this adjustment permitting a convenient and effective 10 control of the pressure on the pans when passing under the revolving cleaning members.

The shaft 47 has each end portion rotatably supported by the bearing 48 carried by a beam 1 at a predetermined point rearwardly of the bearings 29. The shaft 47 has its intermediate peripheral portion reduced, as at 49, to afford an annular chamber when the cylindrical head 50 is applied to said shaft and said head 50 is provided with the radial openings 51 in communication with said compartment so that the oil delivered within the tubular shaft 47 20 through the medium of the feed pipe 52 may be discharged under the influence of centrifugal force upon the bristles 53 radiating from the head 50, said bristles being preferably Russian hog bristles. The head 25 50 is adapted to have about 125 R. P. M. and the oil discharged on said bristles is adapted to be spread upon the pan P so that said pan when taken from the machine is properly greased for a further baking operation. As herein embodied, the delivery 30 pipe 52 leads from a supply tank 54 operatively supported above the oiling brush by the brackets 55 also suitably secured to the bearing 48. The supply pipe 52 is adapted 35 to extend entirely through the tubular shaft 47 and at predetermined intervals longitudinally thereof is provided with the openings 57 through which the oil passes within the bore of the tubular shaft and said shaft 47 is provided with the radial openings 58 40 to permit the oil to pass within the annular chamber 49. In practice, we find it of particular advantage to employ cotton seed oil. The free extremity of the supply pipe 52 45 extends exteriorly of the shaft 47 and is upturned, as indicated at 59, and is provided with the pet cock 60, for purposes which are believed to be self-evident. We also find it of advantage to have interposed in the supply pipe 52 intermediate the tank 54 and the shaft 47 the controlling valve 61. The shafts 18, 28 and 47 coact with their respective bearings in a similar manner and it is therefore believed that the disclosure in Fig. 60 2 will suffice for each of the shafts. As particularly shown in Fig. 2, it is to be observed that the shaft is disposed through a block 62 mounted for vertical sliding movement within the bearing and disposed at opposite sides of said block are the springs 63

whereby it will be perceived that the shaft is capable of a yielding movement in order to compensate for any inequalities or unevenness of the pan passing thereunder. In practice, we find it of particular advantage 75 to have the upper spring 63 of less tension than the lower spring. We also find it of advantage to employ the endwise adjustable members 64 suitably threaded through the bearings and engageable with the block 75 62 to maintain the same against vertical movement when it is desired to maintain the shaft in a fixed position. The block 62 is also provided with the lubricating cup 65 so that the shaft may be suitably lubricated. 80 A similar mounting for the shafts 18 and 28 permit the scraping brush and wiping brush to also have yieldable movement in order to compensate for any inequalities or unevenness of the pan passing thereunder. 85 Positioned in advance of the scraping brush and in advance of the wiping brush is the suction head 74 of a width substantially equal to the width of the respective brushes and having its entrance mouth 75 90 disposed upwardly and terminating in close proximity to the brush and said heads are in communication with a common conduit 76 leading to the suction fan 77 supported by the platform 24. The discharge spout 95 81 of the fan delivers within the box 82, the upper portion of which being perforated, as indicated at 83, while the lower part thereof is provided with the removable drawer 84. It will at once be perceived 100 that the waste material separated from the pans by the scraping brush and wiping brush will be collected by the suction head 74 and carried within the box 82 and deposited within the drawer 84. We also 105 find it of advantage to provide each of the heads 74 with the flexible strip 85 preferably of canvas and which is adapted to rest upon the pan to prevent any waste matter being drawn past the head. It will also be 110 understood that the strip 85 possesses sufficient weight as to protect itself against the suction action of the fan 77. Each of the heads 74 at the ends thereof are provided with the depending brackets 74a suitably secured to the inner faces of the side beams 1 whereby said head is fixedly maintained in its applied position. 115

It will also be understood that the perforations 83 within the box 82 possess an aggregate area in excess of the bore of the discharge spout 81 so that the air can escape from the box and the waste matter dropped within the drawer 84. The shafts 18 and 47 together with the fan 77 are adapted to 120 be operated in any convenient manner and it will be perceived that the shaft 28 will be caused to operate through the connection afforded by the chain 26.

From the foregoing description, it is 130

thought to be obvious that a pan cleaning machine constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several parts herein shown in carrying out our invention in practice.

We claim:

1. A device of the class described including an oiling brush, said oiling brush consisting of a tubular shaft having its intermediate portion reduced in diameter, said reduced portion being provided with openings, a head secured to the shaft and provided with openings in communication with the annular chamber afforded by the reduced portion of the shaft, bristles radiating from the head, and a pipe leading from a suitable source of oil supply and disposed through the tubular shaft, said pipe being of a diameter less than the diameter of the

bore of the tubular pipe and being provided with openings.

2. A device of the class described including an oiling brush, said oiling brush consisting of a tubular shaft having its intermediate portion reduced in diameter, said reduced portion being provided with openings, a head secured to the shaft and provided with openings in communication with the annular chamber afforded by the reduced portion of the shaft, bristles radiating from the head, a pipe leading from a suitable source of oil supply and disposed through the tubular shaft, said pipe being of a diameter less than the diameter of the bore of the tubular pipe and being provided with openings, the free end of the pipe extending exteriorly of the tubular shaft and terminating in an upturned portion, and a valve interposed in said upturned portion.

In testimony whereof we hereunto affix our signatures in the presence of two witnesses.

JOHN SERAGE RITCHHEY.
CLYDE PRESTON WAGNER.
